UNITED STATES PATENT OFFICE.

GEORGE L. SKOLFIELD, JR., OF CHESTER, PENNSYLVANIA.

RIVETING MACHINE.

Application filed January 29, 1923. Serial No. 615,522.

To all whom it may concern:

Be it known that I, GEORGE L. SKOLFIELD, Jr., a citizen of the United States, residing in Chester, Delaware County, Pennsylvania, have invented certain Improvements in Riveting Machines, of which the following is a specification.

My invention relates to certain improvements in riveting machines known as "bull 10 riveters."

One object of my invention is to provide a riveter of this type so that large work can be riveted accurately and quickly.

A further object of the invention is to 15 design the riveter so that a carriage can support the article to be riveted, the carriage being controlled from a point at the riveting dies.

A still further object of the invention is 20 to provide means for moving the carriage longitudinally and for rotating the article to be riveted, which is mounted on the carriage.

Another object of the invention is to 25 provide means for controlling the movement of the riveting dies and the movement of the body of the riveter.

In the accompanying drawings:

Fig. 1 is a side view of my improved riveting machine, showing a pipe in position 30 to be riveted;

Fig. 2 is a plan view;

Fig. 3 is an enlarged transverse sectional view on the line 3—3, Fig. 1;

Fig. 4 is a transverse sectional view on the line 4—4, Fig. 1;

Fig. 5 is a plan view of a portion of Fig. 4;

Fig. 6 is a diagrammatic side view showing 40 the means for controlling the lower riveting die and the plunger for moving the frame of the riveter on its pivot, and also showing the means for controlling the rotary movement of the work on the carriage;

Fig. 7 is a diagrammatic view showing 45 the air pipes and the control mechanism leading to the air cylinder and the means for controlling the longitudinal movement of the carriage;

Fig. 8 is a plan view of the frame of the 50 riveter in dotted lines and showing the mechanism in full lines, which controls the movement of the carriage and the rotation of the work;

Fig. 9 is an enlarged side view of the 55 upper die showing one of the foot levers of the control mechanism;

Fig. 10 is an end view of the upper die showing the control mechanism;

Fig. 11 is a sectional elevation of a portion 60 of the carriage illustrating the extent of vertical adjustment; and

Fig. 12 is a transverse sectional view illustrating my invention arranged to rivet 65 flat plates and flat sections.

Referring to the drawings, 1 is a riveting machine having an upper member 2 and a lower member 3. The riveting machine is mounted on a pivot 4 carried by a frame 5 secured to the foundation 6. The two members 2 and 3 are spaced apart to form a throat 7 to allow the article to be riveted to be moved into the throat as the riveting progresses. The lower member 3 carries the cylinder 8, in which is the plunger 9 carrying the movable die 10. The fixed die 11 is mounted on the upper member 2. On each side of the riveter are rails 12, which are mounted on suitable foundations. Sup-

ported by the rails is a carriage 13. This 70 carriage consists of hollow side beams 14 having bearings 15 for the axles of the flanged wheels 16 and 16^a that travel on the rails 12. The two side frames 14 are connected at the rear by a cross member 17. It 75 will be understood that a clearance space

must be allowed between the side members of the carriage to permit the carriage to pass on each side of the lower member 3 of the riveter. In some instances, the forward 80 ends of the side members may be connected by a detachable cross piece. Mounted on the side frames 14 are frames 18 supported at

intervals by blocks 19. These frames are 85 rectangular in cross section. On the frames 18 are base plates 20 on which are adjustably mounted the bearings 21 for the longitudinal shafts 24. On these shafts are

rollers 22 for the cylinder, or other form, a, 90 to be riveted. The bearings can be adjusted towards and from each other by set screws 23, which are mounted in the lugs on the plate 20. The screws are connected to the

bearings so that, on turning the screws, the 95 bearings can be moved towards and from the center of the carriage in order that they may be adjusted to accommodate cylinders

of different diameters. 100
105

The frame 18 can be adjusted vertically by screws 70 that are mounted in bearings 71 in the frame 18 and which extend through threaded openings in heavy nuts 72 secured to the frame 14. On turning the screw, the frame and the rollers carried thereby can be adjusted vertically. The extent of movement is shown in Fig. 11.

The blocks 19 are in the form of wedges that can be adjusted laterally to take the weight off the screws after the screws have adjusted the frames 18. In some instances, the blocks 19 may be removed, as in Fig. 11.

In Fig. 12 is shown the mechanism arranged to rivet a flat section. In this view, the frames 18 are omitted, the bearings 21 for the longitudinal shafts 24 being located on wedges 19^a resting on the side frames 14. When the flat sections are extended, the outer portions may be supported on trolleys 73 mounted on rails 74.

In Fig. 12, supporting beams 75 are shown, which rest on the rollers 22 and on rollers 76 on the trolleys 73. The section to be riveted is carried by the rails and the rails, with the sections thereon, can be moved laterally by turning the shafts 24. The carriage can be moved longitudinally by operating the mechanism previously described.

In the present instance, at each side of the carriage are centering plates 25, which are mounted in brackets 26 firmly secured to the foundation. The plates are flanged at 27. On the brackets 28, projecting from the frames 14, are two guide wheels 29, which bear upon either side of the flange 27 of the plates 25 and hold the carriage against lateral movement, thus centering the carriage in respect to the riveting dies. In some instances, these plates may be dispensed with.

At the rear end of the carriage 13 is an electric motor 30. This motor drives the mechanism for moving the carriage and for turning, or moving the work on the carriage.

31 designates a hydraulic variable speed gear of known construction, which controls the mechanism for transmitting power from the motor to a shaft 77 geared to one of the axles 78, Figs. 4 and 5, on which are the wheels 16.

79 designates another hydraulic variable speed gear controlling the mechanism through which power from the motor 30 is transmitted to the longitudinal shafts 24. On a shaft 80 is a bevel pinion 81, which meshes with a bevel wheel 82 of a vertical shaft 83, geared to a transverse shaft 84, which, in turn, is geared to the two longitudinal shafts 24.

The operator occupies a seat 32 secured to the end of the upper member 2 of the riveter, as shown in Fig. 1. Two hand levers 33 and 34, one on each side of the mem-

ber 2, are connected to the hydraulic speed gears mentioned above, which control the power from the motor 30.

The lever 33 is connected to the speed gear 31 controlling the power to the axle 78. The lever 34 is connected to the speed gear, which controls the power that drives the shaft 24.

The lever 33 is mounted on a short shaft 85 geared to a longitudinal shaft 86 mounted in bearings 87 on the upper member 2 of the riveter, Fig. 8. The shaft 86 is geared to a vertical shaft 88, Fig. 6, which, in turn, is geared to a longitudinal shaft 89 at the base of the riveter. This shaft extends under the carriage and has a telescopic section 89^a, which is mounted in bearings on the carriage, and geared to a shaft 90 connected to a short shaft of the speed change gear 79, as clearly shown in Fig. 4. When the lever 33 is operated, the shaft 90 is rotated, imparting movement to the mechanism of the speed change gear, causing the cylinder to rotate on its carrying rollers.

The lever 34 is mounted on the left hand side of the riveter in the present instance and is secured to a short shaft 91, geared to a longitudinal shaft 92, mounted in bearings 93 on the upper member 2 of the riveter. This shaft 92 is geared to a vertical shaft 94, which, in turn, is geared to a longitudinal shaft 95 extending under the carriage, Fig. 7. The shaft 95 has a telescopic section 95^a mounted in bearings on the carriage and is geared to a shaft 96 connected to the mechanism of the speed change gear 31, Fig. 4, so that, when the lever 34 is manipulated, the carriage can be moved longitudinally in either direction.

35 and 36 are foot levers that control the mechanism of the riveter. The lever 35 controls the mechanism for supplying fluid under pressure to the cylinder in which the plunger of the lower die is mounted. The lever 35 controls the mechanism for adjusting the riveter on its pivot 4. The lever 36 is connected by a rod 37 to a lever 38 pivoted at 39 and held yieldingly in position by a spring 40. A rod 41 connects the lever 38 with an arm 42 of a four-way air valve 43. Communicating with this valve is an air supply pipe 44, which is also connected to an air pressure device. Communicating with the valve 43 are two pipes 45 and 46, which communicate with the air cylinder 47. The pipe 45 communicates with the lower end of the air cylinder, and the pipe 46 communicates with the upper end of the air cylinder, as shown in Fig. 7. The air cylinder 47 is pivoted at 48 and has a plunger attached to a rod 49 connected by a pivot pin 50 to a head 51 secured to the under side of the lower member 3 of the frame of the riveter.

Pivoted to the head 51 is a plunger 52 extending into a cylinder 53 pivoted at 54 to

a bearing on the foundation. Communicating with the bottom of this cylinder is a pipe 55 leading to a hydraulic accumulator 56. The pipe 55 has a branch 57, which 5 communicates with a hand pump 58. While the hand pump is illustrated in the drawings, it will be understood that it may be a power driven pump, if desired. The accumulator balances the overhanging portion of 10 the riveter. The pivot 4 snugly fits its bearings so that the riveter will remain in the position to which it is adjusted.

The foot lever 35 is connected by a rod 59, Fig. 6, to a lever 60, which, in turn, is 15 connected by a rod 61 to the arm of a control operating valve 62. This control valve is connected to a pilot slide valve 63 having a pipe 64 communicating with an air reserve tank. A pressure reducing valve 65 20 is located in this pipe.

The valve 63 is connected to the lower end of the riveting cylinder 8 at the end of the member 3 by a pipe 97 and with the upper end of said cylinder by a pipe 98. This is 25 the pull back pipe and the pressure returns the lower die after it has compressed the rivet, Fig. 6.

The operation of the mechanism is as follows: In the present instance, the riveter 30 is shown arranged for riveting sections of large cylinders, or pipes. As the carriage is mounted on rails, it is free to move to and from the riveter. The upper member 2 of the riveter extends freely into the open 35 end of the pipe. The pipe is mounted on the side rollers secured to driven shafts, and mechanism is provided for turning the pipe to bring successive holes in position to receive a rivet. The two movements just described allow the operator to adjust the 40 work accurately and quickly in respect to the fixed riveting head.

The operator is stationed in front of the riveting head. In the present instance, a 45 seat 32 is secured to the end of the upper member 2, as illustrated in Fig. 1. The two hand levers 33 and 34 control the movement of the carriage and the work. The foot levers 35 and 36 are located on either 50 side of the member 2 and are connected, one to the riveting mechanism, and one to the means for oscillating the riveter about its pivot 4 to adjust the riveter vertically in respect to the work.

55 In riveting, the operator first locates the holes in the work, then drops a rivet in place, after which the work is brought into alignment with the upper die 11. The plunger in the air cylinder 47 is operated to cause the upper die to settle onto the head of the rivet, forcing it into proper position. The plunger 9 is actuated, which causes the lower die to compress the rivet, forming a head.

60 The lower die is retracted and the air

cylinder is again operated so as to raise the upper die of the riveter clear of the head of the rivet. In the meanwhile, another rivet has been placed in a hole and the above operation is repeated.

65 It will be understood that the overhanging portion of the riveter is balanced by the accumulator 56 and the air cylinder 47 moves the upper die into riveting position, or clear of the rivet. The movement of the 70 accumulator in one direction limits the upward movement of the riveter and acts as a stop to bring the upper die to a clearance point required. The amount of clearance can be varied by pumping fluid into the 75 system to raise the accumulator, or allowing fluid to escape to reduce clearance.

80 When a crooked pipe is being riveted, it is necessary to raise, or lower, the machine on its pivot. This raising or lowering is 85 accomplished by allowing a certain amount of fluid to escape from the balancing cylinder 53, or by forcing fluid into the balancing cylinder from the accumulator. If an extended movement is desired, a hand pump 90 58 may be used to lift the accumulator.

95 In some instances, it may be desirable to locate the operator under the work. In this case, the operating mechanism is carried by the lower member 3. While certain mechanism, including the variable change speed gear, for moving the carriage and for turning the rollers is illustrated, other mechanism may be provided without departing 100 from the essential features of the invention.

105 While the above invention is described as a "riveting machine", it will be understood that punching dies may be substituted for the riveting dies and the machine used for punching.

I claim:

1. The combination in a riveting machine, 110 of a frame having upper and lower members spaced apart to form a throat; riveting dies at the ends of said members; a pivot for the frame; means for counterbalancing the frame; and power means, under the control of the operator, for oscillating the frame on its pivot.

115 2. The combination in a riveting machine, of a frame having upper and lower members spaced apart to form a throat; riveting dies at the ends of said members; a pivot for the frame; means for counterbalancing the frame; means, under the control of the operator, for oscillating the frame on its pivot; 120 independent means for bringing the holding die onto the rivet; and means for operating the riveting die.

125 3. The combination in a riveting machine, of a frame having upper and lower members spaced apart to form a throat; riveting dies at the ends of said members; a pivot on which the frame is mounted; and manually operated means mounted on one of the mem- 130

bers of the frame near its end for controlling the riveting die and for adjusting the frame to the work.

4. The combination in a riveting machine, of a pivoted frame having upper and lower members spaced apart to form a throat; a fixed die on one of said members; a cylinder on the other member; a plunger therein; a riveting die carried by the plunger; means for admitting fluid to the cylinder for operating the die; an air cylinder; and means connected to the air cylinder and to the frame for oscillating the frame on its pivot; and means for counterbalancing the frame.

10 5. The combination in a riveting machine, of a pivoted frame having extended upper and lower members spaced apart to form a horizontal throat; a fixed die carried by one of said members; a cylinder on the other member; a plunger in the cylinder; a movable die on the plunger in line with the fixed die; means at the ends of said members controlling the movement of the plunger; two cylinders connected to the frame; a counter-25 balancing accumulator connected to one of said cylinders for counterbalancing the frame; air pipes connected to the other cylinder; and means at the ends of one of the members of the frame for controlling the 30 air to adjust the fixed die in respect to the work.

6. The combination in a riveting machine, of a frame having upper and lower members spaced apart to form a horizontal 35 throat; a riveting die at the outer end of each member; a carriage for the work; means for moving the carriage longitudinally; means on the carriage for moving the work laterally in respect to the riveting 40 dies; means for locating the dies in respect to the work; and control mechanism for the several means located on one of the members of the frame at a point near the riveting dies.

45 7. The combination in a riveting machine, of a frame having upper and lower members spaced apart to form a throat; riveting dies carried by said members; longitudinal rails; a carriage mounted on said rails; 50 means for moving the carriage; side beams on the carriage; screws for raising and lowering the beams; a longitudinal shaft on each beam; means for rotating the shafts; rollers on the shaft for supporting the work;

and control mechanism at the riveting dies 55 for the carriage, operating mechanism, and the mechanism for rotating the shafts.

8. The combination in a riveting machine, of a frame having upper and lower members spaced apart to form a horizontal 60 throat; a riveting die on the end of each member; means for moving the lower die towards and from the upper die; an operator's station at the end of one of the members; a carriage for the work; means for moving the carriage longitudinally; means, on the carriage, for moving the work laterally; and devices mounted on the upper member of the frame near its end for controlling the movement of the carriage and the work and 65 for controlling the riveting dies.

9. The combination in a riveting machine, of a pivoted frame having upper and lower members spaced apart to form a throat; a fixed die carried by the upper member; a cylinder carried by the lower member; a plunger in said cylinder; a die carried by the plunger; an operator's station at the end of the upper member; means on the frame at the station, for controlling the movement 70 of the lower die; means, also on the frame at the station, for turning the frame on its pivot; a carriage for the work; means for moving the carriage longitudinally; means for moving the work laterally on the carriage; and control mechanism on the upper frame near the operator's station for the carriage and for the means for rotating the work.

10. The combination in a riveting machine, 90 of a pivoted frame having upper and lower members spaced apart to form a horizontal throat for the work; means for balancing the frame; means for adjusting the frame to the work; riveting dies at the 95 end of the upper and lower members of the frame; foot levers on the frame at the riveting dies for controlling the movement of one of the riveting dies and the frame adjusting means; a longitudinally movable 100 carriage; longitudinal shafts on the carriage for supporting the work; means for rotating the shafts; and control hand levers on the frame near the dies for controlling the movement of the carriage and the work supporting shafts.

GEORGE L. SKOLFIELD, JR.
